JOURNAL BOX WEDGE AND BRASS

Thomas H. Symington, Baltimore, Md., assignor
to T. H. Symington & Son, Inc., Baltimore, Md.,
a corporation of Maryland

Application December 22, 1930
Serial No. 504,158

9 Claims. (Cl. 308—57)

The invention relates to journal boxes for railway car trucks, particularly, but not necessarily, to that type wherein the journal boxes are integral with the side frames, and has special reference to the construction of the wedges interposed between the roof of the box and the journal.

It is well known that with the standard type of wedge and brass in use today there is considerable movement of the wedges with respect to the box, this movement being, contrary to what might be expected, transversely of the axle instead of longitudinally thereof. The brass which contacts with the journal has a neat fit within the standard type of wedge and about one-fourth inch clearance from the inside guide lugs of the journal box, thus permitting a total movement of the wedge of one-fourth inch. The principal time of such movement in one direction is when the wheels become unloaded due either to car roll or vertical oscillation of the car body with the simultaneous application of the brakes pressing both wheels away from the center of the car. It has also been found that movement in the other direction or movement of the wheels toward the center of the bolster occurs when travelling at high speed and unloading of the wheels from vertical oscillation or car roll takes place at the same time the wheels strike a guard rail. An inspection of numerous integral type journal boxes after a comparatively short use clearly discloses the fact that this movement of the wedges within the journal boxes wears away the roof of the box rapidly, a circumstance which is serious and alarming owing to the fact that as the journal boxes are integral with the side frame the destruction of the box roofs necessitates discarding the entire side frame.

It is with the above facts in view that I have devised the present invention which has for its general object the provision of a novel wedge structure so constructed that it will remain immovable, that is to say non-slidable, at the proper position within the journal box, the arrangement being such that the brass may move instead so as to take the wear, the journal box roof being therefore relieved of the abrasive action caused by movement of the wedge and remaining in undamaged perfect condition for an indeterminate period of time.

An important object of the invention is to provide in a journal box a wedge of such construction that even though it be placed originally in improper position, that is spaced away from the roof stops or lugs it will be automatically brought

into and anchored at the proper position upon the occurrence of the first impact tending to move the wedge outwardly toward the end of the journal.

Another object of the invention is to provide a wedge having these characteristics but which will yet be free to equalize itself against the roof of the box.

Another object of the invention is to provide a wedge in which the slippage preventing means will operate to keep the center of the radius of the curved top of the wedge on the center line of the side frame.

Still another object of the invention is to provide a wedge and brass combination in which the latter may have limited movement with respect to the former, instead of the customary neat fit, so that any wear will come upon the brass as the brass is of softer material than the wedge, the wedge and journal box being consequently undamaged regardless of length of use.

A further object of the invention is to provide coating means on the wedge and brass which will operate to prevent overturning of the latter in the event of a hot box resulting from a waste "grab" or any other cause.

An additional object is to provide a wedge and brass combination which will be simple and inexpensive to make, easy to install, positive in action, efficient and durable in service, and a general improvement in the art.

To the attainment of the foregoing and other objects and advantages, the invention preferably consists in the details of construction and the arrangement and combination of parts to be hereinafter more fully described and claimed, and illustrated in the accompanying drawings in which:

Figure 1 is a vertical longitudinal section through a journal box equipped with a wedge and brass constructed in accordance with my invention.

Figure 2 is a plan view with a portion of the box broken away and in section to show the top of the wedge.

Figure 3 is a view of a fragment of a side frame and integral journal box, the view showing a portion of the box in elevation with the cover removed and showing a portion of the wedge, brass and journal as well as the box in section, and

Figure 4 is a view partly in end elevation and partly in section showing the brass and wedge on a larger scale.

Referring more particularly to the drawings it will be observed that I have shown a journal

box 10 of the type which is formed integrally with the side frame 11. This box is represented as of the well known A.R.A. standard type and includes a roof 12 equipped with depending stop lugs 13, and sides 14 equipped with inwardly extending inside guide lugs 15. The car journal is indicated at 16. The above described structure being standard, no novelty is claimed for it.

In carrying out the invention I of course make use of a wedge and brass combination interposed between the roof 12 and the journal 16 and both of these elements are of special construction to be described.

In carrying out the invention I provide a wedge 17 which may be of the usual dimensions and which has a curved top surface 18 of any preferred curvature. In actual practice I have found that a radius of twenty-four inches as compared with the customary seventy-two inches is particularly advantageous as it permits a greater equalization of the wedge and provides a greater bearing factor than is actually required, the idea being that the more abrupt curvature will act to insure the center thereof remaining on the center line of the side frame. At its forward end the wedge is disclosed as having an extension 17a apertured at 20 as usual and having a thickened stop flange 21 adapted to abut against the inside roof stop lugs 13. This curvature is longitudinally of the car axle as the wedge is not curved transversely but bears against the roof along what may be considered substantially line contact which permits the equalization above referred to so that the brass 19 beneath the wedge may have proper contact throughout with the journal 16. There is intended to be but little tolerance between the side edges of the wedge and the inside guide lugs 15 so as to reduce the shifting tendency.

At its underside the wedge is formed with a wider recess than usual as shown at 22, the recess being defined by a flat, plane or horizontal wall 23 and downwardly diverging inclined side walls 24, for the reception and accommodation of the brass 19 which has a flat top surface bearing against the surface 23 and which has inclined sides 25 spaced from the walls 24 a suitable distance, one-fourth inch being highly satisfactory in actual practice. Clearly the brass may slide laterally within the wedge instead of fitting neatly therein as is the ordinary practice. As is usual, the brass has a certain tolerance with respect to the inside guide lugs 15 and its movement laterally of the box is limited by engagement of its edges with these lugs. It is intended that the space 26 between the inclined sides of the brass and the inclined walls 24 of the wedge be sufficiently great that when the brass moves laterally it will strike against the inside guide lugs before it contacts with the walls 24 so as to avoid bringing any wear upon the latter.

In order to anchor the wedge with respect to the box so that it cannot shift about and cause wear on the roof, I preferably provide a plurality of teeth 27 in its top, these teeth being formed conveniently on hardened blocks 28 inserted and forged into the top of the wedge at such a location that the teeth will bite into the roof at the center line of the side frame when the wedge is in its forwardmost position with the flange 21 abutting the roof stops 13. Attention is directed to the fact that these teeth have their cutting edges toward the inner side or end of the box, the inclined portions being toward the outer end 75 of the box so that the teeth will be of a ratchet-

like shape capable of permitting the wedge to move outwardly toward the end of the journal while preventing it from moving in the opposite direction. Any desired number of these teeth may be provided though in the present instance I have shown three as this is probably sufficient for the purpose.

In order to prevent any possible overturning of the brass in the event of a hot box arising from any cause, I have disclosed the wedge as provided at opposite sides with ears 29 which are located forwardly or outwardly of the inside guide lugs 15, and have also shown the brass as having lateral projections 30 located below these ears and normally out of contact therewith though capable of engaging thereagainst in the event of any tendency of the brass to turn with the journal. The space 31 between the ears 29 and the projections 30 need actually be only approximately one-sixteenth inch. The reason for this is that it is estimated that by the time the top side of the brass wears down one-sixteenth of an inch, a condition which would result in contact of the projections with the ears 29, the brass itself would be worn out as the maximum wear occurs at the area of contact with the journal.

In assembling, it is intended that when the wedge is applied it be pulled forwardly against the inside roof stop lugs 13 as shown in Figure 1. If, however, this is not done the force on the wedge from actual thrust coming always on the rear end will drive the wedge against the stop lugs, the character and shape of the teeth 27 being such that there will be no cutting action during movement of the wedge in this direction so that this sliding may occur once. After the application of one blow or impact the wedge will remain in this position because the teeth will bite in upon any tendency toward movement in the opposite direction, the teeth being rather ratchet-like in their operation. Owing to the fact that the wedge is thus anchored, so to speak, its bearing against the roof will remain at the most desirable location, namely, at the center line of the side frame. The reduction in the curvature of the top surface of the wedge is an important feature as it should be realized that if a seventy-two inch radius roller cocks a slight amount the load shifts off the center a definite and appreciable amount. The smaller the radius the nearer the center the load is kept for an equal amount of cocking. By making the radius of this top curve say twenty-four inches, the actual load is kept near the center line of the side frame at all times and through the medium of the projecting teeth the wedge is centered in its proper position where it remains constantly.

It will be noted that the brass is freely slideable laterally with respect to the wedge but that the space 26 is greater than the tolerance between the brass and the inside guide lugs, the result of this being that any lateral thrust of the moving brass is taken by the journal box instead of contact occurring between the sides of the brass and the walls 24. Of course the friction between the top of the brass and the under wall 23 of the wedge will result in appreciable wear on the brass but by the time that the top of the brass wears away to a sufficient extent that the projections 30 will contact with the ears 29 the brass will be worn out where it contacts the journal and will be in condition to be discarded.

From the foregoing description and a study of the drawings it will be apparent that I have thus provided a novel combination, construction and

arrangement wherein the roof of the journal box will be positively relieved of wear and the wedge likewise relieved of wear, the benefit being that the journal box will remain in good condition for an indefinite period, and the wedge likewise remain usable for a long time, practically all destructive wear coming upon the brass which must necessarily be replaced from time to time anyway. It is believed that the construction, operation and advantages should be readily apparent to one skilled in the art without further explanation.

While I have shown and described the preferred embodiment of the invention, it should be understood that the disclosure is merely an exemplification of the principles involved as the right is reserved to make all such changes in the details of construction as will widen the field of utility and increase the adaptability of the device provided such changes constitute no departure from the spirit of the invention or the scope of the claims hereunto appended.

Having thus described the invention, I claim:

1. In combination with a journal box and a journal therein, a wedge bearing against the underside of the top of the box and a brass located between the wedge and the journal, and means for preventing sliding movement of the wedge with respect to the box in every direction other than forwardly.

2. In combination with a journal box and a journal extending thereinto, a wedge bearing against the underside of the top of the box, a brass located between the wedge and the journal, and means forming a part of the wedge and projecting thereabove engaging the roof of the box for preventing displacement of the wedge with respect thereto in every direction other than forwardly.

3. In combination with a journal box and a journal extending thereinto, a wedge bearing against the underside of the top of the box and a bearing brass located between the wedge and the journal, and means forming a part of the wedge projecting above the top thereof and cutting into the top of the box for preventing sliding movement of the wedge with respect thereto.

4. In combination with a journal box and a journal extending thereinto, a wedge and a bearing brass arranged in superposed relation and engaging respectively against the top of the box and the journal, the wedge having its top surface curved longitudinally of the journal and provided with means anchoring it to the top of the box for preventing sliding displacement in every di-

rection other than forwardly and enabling it to move forwardly.

5. In combination with a journal box and journal extending thereinto, a wedge engaging against the underside of the top of the box and rockable longitudinally of the journal, means on the wedge engaging the top of the box for preventing sliding movement of the wedge in every direction other than forwardly, and a brass engaging the journal and projecting into the wedge in rectilinear transverse slidable relation thereto.

6. In combination with a journal box and a journal extending thereinto, a wedge engaging the underside of the top of the box, means for preventing sliding movement of the wedge with respect to the box in every direction other than forwardly, said wedge having its underside formed with a recess, and a brass located within said recess and engaging the journal, said brass being capable of rectilinear sliding movement transversely within said recess.

7. In combination with a journal box and journal extending thereinto, the box having a roof with depending stop lugs, a wedge engaged beneath the roof with its outer end in engagement with said stop lugs, a brass between the wedge and the journal and movable with respect to the former, and teeth on the wedge penetratingly engaging within the roof of the box for preventing sliding displacement of the wedge in every direction other than forwardly.

8. In combination with a journal box and a journal extending thereinto, a wedge located beneath the top of the box, a brass located between the wedge and the journal, and teeth on the wedge adapted to penetratly engage the top of the box, said teeth having their upper surfaces inclined downwardly toward the end of the journal whereby the wedge may slide outwardly with respect to the journal but be prevented from reverse sliding movement.

9. In combination with a journal box and a journal extending thereinto, a wedge engaging the underside of the top of the box, a brass slidably mounted within the lower portion of the wedge and engaging the journal, and hardened metallic inserts in the wedge formed with teeth having their upper surfaces inclined downwardly toward the end of the journal and having edges at their inner ends adapted to bite into the top of the box for preventing sliding movement of the wedge in all but one direction.
